US00D942112S

(12) **United States Design Patent** (10) Patent No.: **US D942,112 S**
(45) Date of Patent: **** Feb. 1, 2022**

(54) **CONFECTION WITH MULTICOLOR PATTERN**

(71) Applicant: **Jason Toombs**, Washington, PA (US)

(72) Inventor: **Jason Toombs**, Washington, PA (US)

(73) Assignee: **Jason Toombs**, Washington, PA (US)

(**) Term: **15 Years**

(21) Appl. No.: **29/738,271**

(22) Filed: **Jun. 16, 2020**

(51) LOC (13) Cl. **01-01**

(52) U.S. Cl.

USPC **D1/106; D1/127**

(58) **Field of Classification Search**

(57) **CLAIM**

The ornamental design for a confection with multicolor pattern, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a confection with multicolor pattern;

FIG. 2 is a rear elevational view thereof;

FIG. 3 is a bottom plan view thereof;

FIG. 4 is a left side elevational view thereof;

FIG. 5 is a right side elevational view thereof; and,

FIG. 6 is a perspective view thereof.

1 Claim, 5 Drawing Sheets
